RUNPROOF OR RUN-RESISTANT FULL-FASHIONED OR FLAT-KNIT STOCKING OR BLANK THEREFOR

Ellsworth E. Carlson, Saratoga Springs, N. Y., assignor to Van Raalte Company, New York, N. Y., a corporation of New York

Original application March 4, 1937, Serial No. 128,951. Divided and this application July 7, 1937, Serial No. 152,338

12 Claims. (Cl. 66—178)

This application is a division of my co-pending application Ser. No. 128,951, filed March 4, 1937.

This invention relates to run-proof or run-resistant full-fashioned or flat-knit stockings or blanks therefor.

5 In order that the principle of the invention may be readily understood, I shall disclose several types or embodiments of the said stocking or blank.

10 The stockings or blanks herein disclosed are made basically in accordance with patents already issued to me, among which I particularly refer to the following: No. 1,978,408, Oct. 30, 1934; No. 1,978,409, Oct. 30, 1934; No. 1,978,412, Oct. 15 30, 1934; No. 2,011,267, Aug. 13, 1935; No. 2,014,126, Sept. 10, 1935; No. 2,037,000, April 14, 1936; No. 2,039,283, May 5, 1936, and No. 2,049,994, Aug. 4, 1936.

In the drawings,—

20 Fig. 1 is a plan view of a non-run or strongly run-resistant blank knitted of full width throughout and in accordance with my invention;

25 Fig. 2 is a similar view showing a blank after trimming;

Fig. 3 is a view upon an enlarged scale of the lower portion of the blank shown in Fig. 1 to indicate the presence of the warp threads throughout the entire extent of the said blank;

30 Fig. 4 is a diagrammatic plan view of a heel portion and a part of the fabric adjacent thereto when made by a widening action in alternate courses, this being desirably done by employing mechanism generally of the so-called TW type;

35 Fig. 5 is a plan view of the toe portion of the fabric to indicate diagrammatically the narrowing action;

40 Fig. 6 is a view of the foot portion of the stocking to indicate the seaming along the middle of the bottom thereof, which is continued up the back of the leg;

45 Fig. 7 is a somewhat diagrammatic view to indicate the formation of the heel portions, which I preferably accomplish by using mechanism generally of the so-called TC type; and

Figs. 8 and 9 represent diagrammatically the formation of the heel, which I preferably accomplish by using mechanism of the general TL type.

50 In my patents hereinbefore referred to, I have disclosed a non-run or strongly run-resistant full-fashioned or flat-knit stocking or blank therefor, wherein a warp thread is preferably introduced, one for each needle wale. In certain of 55 said patents, I have disclosed means for laterally

transferring stitches for fashioning the fabric. In certain of said patents the stocking blank is disclosed as knitted of full width throughout. In those patents wherein means for knitting the stocking blank is disclosed, I have among other things disclosed the knitting of a blank or a continuous succession of blanks each knitted of full width down to the toe.

5 In this application, I have disclosed the knitting of the entire stocking blank from the commencement of the welt through the toe, all upon a single-unit single-head machine, the warp threads which render the stocking of a non-run or strongly run-resistant character extending continuously throughout each stocking blank.

10 The machine shown in the patent to Howie and Krieble, No. 1,982,991, is known upon the market as the Wildman single-unit single-head machine. Said machine as now upon the market is of several types known respectively as the TW, the TC and the TL machines. In the said TW machine, 15 the instep stitches are not taken off the needles during the knitting of the heel tabs or members. In the TL type, the instep stitches are taken off the instep needles during the knitting of the heel tabs or members, and then returned to the same 20 needles.

25 To the several types of the Wildman single-unit single-head machines, I have applied mechanism disclosed in my said parent application Ser. No. 128,951 for the introduction of warp threads preferably one to each needle wale, which warp threads are continued in action throughout the knitting of the entire blank, namely, from the commencement of the top welt through the 30 termination of the toe, and in so doing I have made a distinctly novel full-fashioned or flat-knit stocking or blank therefor, of a non-run or strongly run-resistant character throughout, and which is the subject matter of the present application.

35 Where I refer in the specification to a weft thread or a body thread or the like, it is to be understood that such terminology is intended to include the introduction of three or more threads 40 in accordance with the Kaufman method disclosed in the Kaufman Patent No. 1,969,307, August 7, 1934.

45 The stocking blank, shown in its unfinished condition in Fig. 1 and in its trimmed condition 50 in Fig. 2 at 1 and 2 respectively, so far as the portion thereof down to the heel tabs is concerned, is desirably knitted in the manner disclosed in my Patent No. 1,978,408, Fig. 3, and more fully described in my Patent No. 1,978,409, 55

wherein the stocking blank in its unfinished condition is represented in Fig. 37. In said Patent No. 1,978,409 is disclosed a Reading type of full-fashioned knitting machine, whereas the blank shown in Figs. 1, 2 and 3 thereof is made upon the Wildman single-unit single-head machine. In both cases I introduce a separate warp thread to each needle wale throughout the width of the fabric and confine each warp thread to its own 10 needle wale throughout, so that each sinker wale is devoid of a warp thread. While my invention is not limited thereto, I have preferred in practice to introduce a separate warp thread to each needle wale and to confine each warp thread to its own 15 needle wale throughout. While I prefer to knit the stocking blank of full width throughout, my invention is not so limited.

Desirably I employ natural silk threads in the manufacture of the stocking, but my invention 20 is not limited to the use of any particular material. Preferably, however, I do employ natural silk and the body thread or threads may be of such character as to result in chiffon hosiery, but my invention is not so limited. I may employ in the manufacture of chiffon hosiery one 25 thread or more, and the warp threads are also preferably of silk of like character, so that the resulting stocking blank is made of silk throughout, preferably in the gray and subsequently 30 dyed, but my invention may also be employed in the manufacture of ingrain stockings.

In Figs. 1 and 2, the upper welt is shown at 3. Although the stocking blank is knitted of the full width throughout as shown in Fig. 1, stitches 35 are laterally transferred inward both near the knee portion as indicated at 4, 4 in Figs. 1 and 2, and also at the calf portion as indicated at 5, 5 in said figures. In so fashioning the stocking blank, I preferably proceed in the manner fully 40 disclosed in my said Patent No. 1,978,409 and particularly in Figs. 25 to 29 thereof. Each warp thread continues in action without being severed and without the fabric being removed from the machine, from the commencement of the welt 3 down to the extreme lower end of the blank indicated by the line 6—6. In other words, the 45 warp threads are continued, without necessary thread severance, to the toe portion 7 of the stocking, this including not only the instep portion 8 but also the high splice portions 9, the heel 50 tabs or portions 10 and the two portions 11, 11, which when seamed together constitute the under side of the foot, which in this case would result 55 in the manufacture of the French type of foot, to which, however, my invention is not limited, as I may make the foot of the English type. The 60 said blank is desirably reinforced as indicated in Figs. 1 and 2 in the high splice, the heel and the sole of the foot by the introduction of additional threads in a manner which need not be more fully described.

It is unnecessary to show the structure of each 65 stitch of the fabric upon a sufficiently large scale to represent both the body or weft threads and the warp thread as entering into and constituting the same, but it is to be understood that such is the structure herein and hereby disclosed. I have, however, in Fig. 3, represented one characteristic needle wale as representative of each 70 and every needle wale throughout the fabric. In said figure, the weft or body thread is indicated at 12 and the warp thread at 13. The warp thread 13 is introduced at and for the very commencement of the upper welt and continues down 75 through the toe. It is to be understood that in

the operation of the machine the warp threads are continuously introduced stocking blank after stocking blank, so that they are not removed from the warp thread guides or fingers, but are by said guides or fingers constantly introduced into the fabric or fabrics as the same is or are knitted. I have also in said Fig. 3 indicated diagrammatically the character of the fabric not only in the said single representative needle wale but at other portions thereof.

Referring further to Figs. 1, 2 and 3, and also to Figs. 4, 5 and 6, and making reference in this connection to the so-called TW type single-unit single-head machine, it is pointed out that whereas as in all of my patents hereinbefore referred to 15 stitches are laterally transferred inward to effect narrowings (although certain claims of said patents are not so limited), I, in this application, disclose the transferring of stitches outward to widen the fabric. The stitches so transferred 20 outwardly are stitches in the heel tabs 10, 10 of Figs. 1, 2 and 3. In Fig. 4 I have shown diagrammatically one of said heel tabs or portions 10. In order that the said heel tabs or portions may be formed or produced upon a more 25 satisfactory outward inclination to the instep portion, etc. (that is, more nearly assuming a right-angled relation thereto), I desirably laterally transfer outward heel-tab portions of courses of stitches throughout an extensive portion of each of said heel tabs. The stitches so 30 laterally transferred outward are desirably each composed of the warp thread loop and the weft thread loop together composing such stitch, although within the scope of my invention I may transfer outwardly only one of the threads of each of said loops, as, for example, the body or weft thread. Desirably, however, I laterally transfer outward both the warp and the weft 35 thread constituents of each loop where transfer occurs.

Referring more particularly to Fig. 4, the first course in the heel tab or portion is represented diagrammatically at 14. This course consists entirely of non-laterally transferred stitches. 45 The next course 15 knitted in the same direction preferably consists throughout the heel tab or portion of stitches laterally transferred outwardly. The next course 16 knitted in the same direction preferably consists of stitches not 50 laterally transferred, and the next course 17 knitted in said same direction consists of stitches all of which in the heel-tab areas are laterally transferred outwardly. This alternation of non-laterally transferred stitches forming one course 55 and laterally outwardly transferred throughout the heel-tab areas in the next course knitted in said same direction is preferably continued throughout the formation of each heel tab or portion.

Thus, I have disclosed a structure wherein at least one of the threads constituting a stitch (i. e. the warp thread and the body or weft thread) is laterally transferred outward. Such lateral transfer outward occurs throughout an extensive 65 portion of the fabric and is preferably a lateral transfer of both the warp threads and the body or weft thread. Such transfer in the heel tabs or portions occurs in separated courses and desirably in alternate courses knitted in the same direction. Thus, the stocking blank is provided with heel portions whereof alternate courses knitted in the same direction only have laterally transferred outward stitches that are composed 70 both of warp threads and of the body thread or 75

threads. All of the stitches of one or more of the courses in the heel portions are thus laterally transferred outward for the purpose of widening the heel tabs and giving them more nearly a right-angled relation to the instep.

It will thus be understood that I have provided a blank or stocking wherein is provided a series of warp threads one for substantially each needle wale of the fabric and collectively knitted into substantially all the stitches of the needle wales, so that substantially each stitch of the main thread or threads of the fabric has a stitch of a warp thread to render the said fabric of a non-run or strongly run-resistant character, said stocking blank having stitches laterally transferred outwardly.

It will further be understood that as the stocking blank is knitted upon a machine capable of knitting the entire foot and the toe upon the same machine which formed the leg, I have provided a full-fashioned or flat-knit run-proof or strongly run-resistant stocking blank comprising an integrally knitted leg portion, as shown in Figs. 1 and 2, an instep portion 8, heel portions 10, foot-sole portions 11 and a toe portion 7, said blank comprising a main or body thread or threads knitted into all the wales of the said blank from edge to edge thereof and into all the courses of the said blank and a series of warp threads extending integrally (i. e. without necessary thread severance) lengthwise the fabric through the said leg portion, instep, heel, foot-sole and toe. Thus, the said stocking or blank, when knitted upon the said TW type of Wildman full-fashioned machine, has as a continuation formed initially and integrally therewith and without necessary thread severance, an instep portion with initially integral lateral extensions, 11, 11, which together, when seamed as indicated at 18 in Fig. 6, constitute the bottom of the foot, and has a toe 7 constituting an initially integral extension (without necessary thread severance) of said instep portion and said lateral extensions, the warp threads extending without necessary thread severance throughout the entire longitudinal extent of said heel portions 10, the instep portion 8, the foot-sole portions 11, 11 and the toe 7. No thread severance of the weft thread or threads or any of the warp threads is compelled during the knitting of the stocking by the herein described steps of manufacture of the stocking.

The seam in this type of stocking extends along the middle of the bottom of the foot, as indicated at 18 (Fig. 6) and up the back of the leg as indicated at 19 in said figure.

It will be evident from the foregoing that my invention includes a full-fashioned or flat-knit run-proof or strongly run-resistant stocking or blank therefor knitted from a main or body thread or threads extending into all the wales from edge to edge of the fabric and into all the courses of the said stocking or blank, and having a series of warp threads extending lengthwise of the fabric into respective loops in successive courses in different loops of the said main or body thread or threads in such courses; and having at the heel portions laterally outwardly transferred stitches in succeeding courses, the knitting operation continuing from edge to edge of the fabric, so as to provide the instep portion and the sole portions, all initially integrally formed with said heel portions without necessary thread severance. In the knitting operation, I provide at the inner edge of each heel portion, as indicated at 20, 20

in Figs. 1 and 2, an outwardly downwardly extending inclined line of openings, which openings are respectively traversed by certain of said continuous warp threads. The knitting of the said instep portion 8 continues course for course during the knitting of the heel portions 10, 10 (i. e. without taking the instep stitches or fabric off the needles); that is, when producing the fabric upon the said TW type of machine.

Such stocking blank 1 of Fig. 1 has as a continuation formed initially and integrally therewith and without necessary thread severance, an instep portion 8 with initially integral lateral extensions 11, 11, that together, when seamed, constitute the bottom of the foot, as indicated at 21 in Fig. 6, said blank also having a toe 7 constituting an initially integral extension of the said instep portion 8 and said lateral extensions 11, the said warp threads extending without necessary thread severance throughout the entire longitudinal extent of said heel portions 10, 10, instep portion 8, foot-bottom portions 11, 11, and toe 7. The toe is fashioned by lateral transfer of stitches, as indicated diagrammatically at 22 in Fig. 5. These stitches are laterally transferred inward by one-needle narrowings.

Thus, my invention includes in the disclosure thereof thus far referred to, a full-fashioned or flat-knit stocking blank knitted of full width throughout, having a main or body thread or threads knitted into all the wales from edge to edge of the fabric blank and into all portions of the said blank, said stocking blank having a series of warp threads one for substantially each needle wale of the fabric and collectively knitted into substantially all the stitches of the said needle wales, so that substantially each stitch of the main thread or threads of the fabric has a stitch of warp thread to render the said fabric blank of a non-run or strongly run-resistant character, said blank having heel portions knitted upon the blank, which heel portions have stitches of warp and weft threads laterally transferred outward in alternate courses knitted in the same direction.

Referring again to Fig. 3, it will be observed that the heel tabs or heel portions 10 are there diagrammatically indicated as containing outward widenings. The two foot-sole portions 11 are diagrammatically indicated at 23, 23 as having inward narrowings. The toe portion 7 is there shown as having toe narrowings 22, 22^a, which are preferably one needle narrowings. Throughout the knitting of the entire fabric shown in Figs. 1, 2 and 3, each warp thread continues without interruption in its own needle wale, as explained in my said patents.

It is to be understood that in knitting the fabric herein disclosed, there is throughout the same a stitch measuring of the weft thread and an accurate apportionment of the warp threads in all the stitches, as fully disclosed in my said Patent No. 2,049,994. The same principle of stitch measurement of the weft thread and accurate apportionment of the warp threads is herein employed by me, as disclosed in my said patent.

I preferably knit the welt at the top of the stocking from a body, main or weft thread that is heavier or of a larger diameter or greater denier than the thread or threads from which other parts of the stocking are knitted, as, for example, the leg and instep. Desirably also the heel is knitted of a heavier weft thread or threads than the main or weft thread of the leg. I impart less tension to the warp threads, while they

are being incorporated into stitches made from the heavier weft thread or threads, than I do to the said warp threads while they are being incorporated into the stitches which are made from a weft or body thread which is of less diameter or smaller denier such as in the leg and instep. In accordance with my invention, I proportion the tension upon the warp threads in inverse relation to the size, weight or diameter of weft or body thread or threads, thus increasing the longitudinal expansibility of the fabric particularly with respect to those portions of the fabric having the heavier weft or body thread or threads, such, for example, as the top welt.

My invention, however, is not limited to lessening the tension upon the warp threads only in the top welt (which includes the so-called shadow welt) and in the heel, since one of my purposes in providing a heavier weft thread at desired points is to resist special strains which may and do occur elsewhere than in the upper welt or in the so-called shadow welt, as, for example, at the knee when bent, which special strains are, in part at least, relieved by introducing the warp threads under less tension at areas subjected to special strain in use. Moreover, it is to be noted that the position or location of the upper welt with respect to the knee, when the stocking is worn, may vary with different makes or styles of stockings.

The foregoing completes the description of the formation of the non-run stocking or blank therefor when made upon the so-called TW type of Wildman machine. In the TW type, it has been hereinbefore pointed out by me that during the knitting of the heel portions the knitting also continues upon the instep, or, in other words, the stitches are not taken off the instep needles during the knitting of the heel portions.

I will next describe the knitting of a stocking blank upon what is termed the TC and TL forms. An outstanding difference between the TW form on the one hand and the TC and TL forms on the other, is that when the knitting operation has progressed to the commencement of the heel portions, the stitches are taken off the instep needles and held out of action temporarily, the said stitches being restored to the instep needles substantially upon the completion of the heel portions.

So far as the introduction of the warp threads into the fabric is concerned, the action is essentially the same in all three of said forms, namely, the TW, TC and TL, and therefore it will be unnecessary to repeat the description with respect thereto.

I will sufficiently refer to the heel construction of both the TC type and the TL type, the former being shown in Fig. 7 and the latter being shown in Figs. 8 and 9.

Referring to Fig. 7, the lower part of the ankle portion (namely, the portion just preceding the commencement of the heel portions) is represented at 24. When the commencement of the heel portions is reached, the instep stitches are taken off the needles by mechanism employed therefor. Then the two heel portions 25, 26 are knitted as integral continuations of the leg portion. The said heel portions are knitted without any widening action whatever, as was done in connection with the TW type. Upon the completion of the said heel portions, the instep stitches are transferred back to the needles and the said two heel portions 25, 26 are topped onto the

proper needles, so that the footsole portions may be knitted as continuations of said heel portions after said heel portions have been so topped onto the needles. The operation of knitting the instep or top of the foot continues and at the same time there are knitted as initially integral lateral extensions of said instep, the two parts 27, 28 just above referred to, and which together constitute the bottom of the foot. Then the toe portion 29 is knitted, desirably in the same manner as shown in Fig. 5, said toe portion thus being an initially integral extension of the said instep portion and of said lateral extensions 27, 28. It will be noted that the warp threads extend throughout the entire fabric shown in Fig. 7, and that the warp threads extend without necessary thread severance throughout the entire longitudinal extent of said heel portions, the instep portion, the foot-bottom portions and the toe, excepting for the severance of warp threads between or with respect to the heel portions 25, 26 and the sole portions 27, 28. The blank is then seamed up along the bottom of the foot and the back of the leg. According to the TC type, it is necessary to cut the fabric at the end of the heel tabs to turn them at right angles for topping, the cut being made in front of the needles so that some fabric remains thereon.

The knitting of the heel portions, etc. according to the TL type is indicated in Figs. 8 and 9. As there shown, the knitting proceeds until the lower part of the ankle portion is completed as indicated at 30. Thereupon the instep stitches are taken off the needles in a manner similar to that just referred to, and the knitting of the two heel portions 31, 32 is proceeded with. Substantially at the end of what constitutes the heel portions, the instep stitches are put back on the instep needles. There is, however, no topping action employed, but the heel is completed by what is known as a looping action, which is done after the knitting of the blank is completed. Therefore, the knitting operation proceeds from this point onward as described with respect to the TC form shown in Fig. 7, so as to complete the top of the foot, the lateral extensions thereof which form the bottom of the foot, and the toe. In knitting the heel portions 31, 32, I knit an additional portion on each heel portion to provide a looping finger-hold including a loose course.

The two heel portions as they appear after the completion of the blank, but before the cutting and seaming action, are indicated in Fig. 8 at 31, 32, 33, the numeral 33 indicating the bunched-up or looped-up portions of the heel tabs, which bunched-up or looped-up portions are subsequently trimmed or cut out prior to the looping indicated at 34. In Fig. 9, I have indicated that each heel portion is cut through at the termination thereof and then turned into a lateral position, whereupon the lateral edge of each heel portion is looped or seamed as indicated at 34 onto the commencement of the bottom-foot portions of the fabric.

It will be understood that in this type of stocking when made in accordance with my invention, the warp threads are continuous throughout the entire fabric from the initial introduction of the said threads down to the completion of the fabric. There is, of course, a necessary severance of the warp threads pertaining to the heel portions and the foot-bottom portions by the action of cutting the heel portions across, as indicated in Fig. 9, for the looping or seaming action.

Referring again to the knitting of the fabric

according to the TC type, as shown in Fig. 7, it will be understood that the warp threads continue throughout the heel portions. In performing the topping action, the inner lateral edge of each heel portion is topped upon the needles and the knitting of the two foot-bottom sections or portions is proceeded with as already described.

In knitting the said heel portions, the warp threads are introduced each into a separate 10 needle wale of the said heel portions. In other words, each and every stitch throughout the entire fabric, both of the TC form and the TL form, contains a warp stitch, this being also true of the TW form already described. In the so-called TW 15 type, the instep stitches are not taken off the needles during the knitting of the heel portions. In both the TC and TL types, said instep stitches are taken off the needles at the very commencement of the knitting of the heel portions and are 20 restored to the same needles upon the completion of said heel portions.

While I have described the full-fashioned or flat-knit stocking or stocking blank of my invention as knitted upon a single-unit single-head 25 machine, I desire it to be understood that I may knit the stocking or stocking blank of my invention upon any machine or machines capable of performing the necessary operations to produce the same, whether the machine be a single-unit 30 single-head machine, or a single-unit multiple-head machine, or a single-head machine, or a multiple-head machine. While I have specifically described the knitting of the heel in accordance with the so-called TW, the TL, and/or the 35 TC types of Wildman machine, my invention is not limited to the knitting of the heel portion or portions in accordance with any of said types excepting as certain of the claims definitely so specify.

40 My invention as herein disclosed does not exclude but would permit the throwing of the warp threads out of action during the knitting of the toe portion and/or the throwing of the warp threads out of action for a few courses when 45 making the loose courses in the heel or toe for looping purposes. Inasmuch as a distinct loose course is not as satisfactorily made when the warp threads are knitted in with the weft thread, rendering it difficult to loop, I may, within the 50 scope of my invention, make said loose courses wholly of the weft thread or threads.

Neither is my invention limited to narrowing at every course in the toe portion, since within the scope thereof I may narrow at intervals as in 55 every other course, thus relieving strain on the yarn or thread in transferring the stitches. By knitting in a plain course between transferred courses, strain upon the yarn or thread is relieved.

Having thus described certain embodiments of 60 the stocking and stocking blank of my invention, and the best mode known to me for making the same, it is to be understood that although specific terms are employed, they are used in a generic and descriptive sense and not for purposes 65 of limitation, the scope of the invention being set forth in the following claims.

I claim:—

1. A full-fashioned or flat-knit run-proof or 70 strongly run-resistant stocking or blank therefor, integrally knitted in one piece from the top of the stocking through the instep and toe and including the entire foot portion, without thread severance being compelled by the steps of stocking manufacture, said stocking or blank comprising a main or body thread or threads knitted

into all the wales from edge to edge of the fabric throughout the length thereof, and a series of warp threads extending each in an unsevered continuous condition lengthwise the fabric and respectively knitted in loops in successive courses in different loops of said main or body thread or threads in such courses.

2. A full-fashioned or flat-knit run-proof or 10 strongly run-resistant stocking or blank therefor, integrally knitted in one piece from the top of the stocking through the instep and toe and including the entire foot portion, without thread severance being compelled by the steps of stocking manufacture, said stocking or blank comprising a main or body thread or threads knitted 15 into all the wales from edge to edge of the fabric throughout the length thereof, and a series of warp threads one for substantially each needle wale of the said fabric each extending in an unsevered continuous condition lengthwise the fabric and collectively knitted into substantially all 20 the stitches of all said needle wales, to render the fabric of a non-run or strongly run-resistant character.

3. A blank for a full-fashioned or flat-knit run- 25 proof or strongly run-resistant stocking integrally knitted of full width throughout in one piece from the top of the blank through the instep and toe and including the entire foot portion, without thread severance being compelled by the steps of 30 stocking manufacture, said blank comprising a main or body thread or threads knitted into all the wales from edge to edge of the fabric throughout the length thereof, and a series of warp threads extending each in an unsevered continuous 35 condition lengthwise the fabric and respectively knitted in loops in successive courses in different loops of said main or body thread or threads in such courses, said blank also including heel portions each having a multiplicity of stitches 40 laterally transferred outwardly.

4. A full-fashioned or flat-knit run-proof or 45 strongly run-resistant stocking or blank therefor provided with a top welt, the said stocking or blank being integrally knitted in one piece from 50 the commencement of said welt through the toe without thread severance being compelled by the steps of stocking manufacture, said stocking or blank therefor comprising a main or body thread or threads knitted into all the wales from edge 55 to edge of the fabric throughout the leg thereof, and a series of warp threads, one for substantially each needle wale of the said fabric and collectively knitted into substantially all the stitches of said needle wales, so that substantially each 60 stitch of the main thread or threads of the fabric has a stitch of a warp thread, to render said fabric of a non-run or strongly run-resistant character, said stocking or blank having a top welt and each of said warp threads extending continuously 65 from the beginning of the welt to the opposite end of the fabric and knitted respectively into the leg, instep, heel, sole and toe of the stocking or blank.

5. A full-fashioned or flat-knit run-proof or 70 strongly run-resistant stocking or blank therefor 65 comprising a main or body thread or threads knitted into all the wales from edge to edge of the fabric and into all the courses of the stocking or blank, and a series of warp threads extending lengthwise said fabric and respectively knitted in 75 loops in successive courses in different loops of said main or body thread or threads in such courses, said stocking or blank having stitches composed both of warp threads and the body thread or threads laterally transferred outward. 75

6. A full-fashioned or flat-knit run-proof or strongly run-resistant stocking or blank therefor comprising a main or body thread or threads knitted into all the wales from edge to edge of the fabric and into all the courses of the stocking or blank, and a series of warp threads extending lengthwise said fabric and respectively knitted in loops in successive courses in different loops of said main or body thread or threads in such courses, said stocking or blank having heel portions, stitches whereof composed both of warp threads and the body thread or threads are laterally transferred outward.

7. A full-fashioned or flat-knit run-proof or strongly run-resistant stocking or blank therefor comprising a main or body thread or threads knitted into all the wales from edge to edge of the fabric and into all the courses of the stocking or blank, and a series of warp threads extending lengthwise said fabric and respectively knitted in loops in successive courses in different loops of said main or body thread or threads in such courses, said stocking or blank having heel portions whereof alternate courses only, knitted in the same direction, have laterally transferred outward stitches that are composed both of warp threads and the body thread or threads.

8. A full-fashioned or flat-knit run-proof or strongly run-resistant stocking or blank therefor comprising a main or body thread or threads knitted into all the wales from edge to edge of the fabric and into all the courses of the stocking or blank, and a series of warp threads extending lengthwise said fabric and respectively knitted in loops in successive courses in different loops of said main or body thread or threads in such courses, said stocking or blank therefor having a toe portion knitted integral with the leg portion and having said warp threads extending integrally (i. e. without necessary thread severance) through the leg and the toe, the said toe portion and all the warp threads thereof being unsevered continuations of the weft thread and of the warp threads existing in some preceding portion of the stocking.

9. A full-fashioned or flat-knit run-proof or strongly run-resistant stocking blank comprising integrally knitted leg portion, instep, heel portions, foot-sole and toe, said blank comprising a main or body thread or threads knitted into all the wales of the said blank from edge to edge thereof and into all the courses of the said blank and a series of warp threads extending integrally lengthwise the said fabric through the said leg portion, instep, heel, foot-sole and toe, the said toe portion and all the warp threads thereof being unsevered continuations of the weft thread and of the warp threads existing in some preceding portion of the stocking.

10. A full-fashioned or flat-knit run-proof or strongly run-resistant stocking or blank therefor, integrally knitted in one piece from the top of the stocking through the instep and toe and including the entire foot portion, without necessary thread severance, said stocking or blank comprising a main or body thread knitted into all the wales from edge to edge of the fabric throughout

the length thereof, and a series of warp threads extending each in an unsevered continuous condition lengthwise the fabric and respectively knitted in loops in successive courses in different loops of said main or body threads in such courses, said stocking having an integral top welt, the main or weft thread whereof is heavier than the corresponding thread or threads for the leg and instep, the said warp threads being in the completed fabric under less tension at the places where they are incorporated into stitches made from said heavier main or weft thread, than they are where incorporated into stitches made from the said lighter body or weft thread or threads.

11. A full-fashioned or flat-knit run-proof or strongly run-resistant stocking or blank therefor, integrally knitted in one piece from the top of the stocking through the instep and toe and including the entire foot portion, without thread severance being compelled by the steps of stocking manufacture, said stocking or blank comprising main or body threads knitted into all the wales from edge to edge of the fabric throughout the length thereof, and a series of warp threads extending each in an unsevered continuous condition lengthwise the fabric and respectively knitted in loops in successive courses in different loops of said main or body threads in such courses, said stocking having an integral, turned top welt, the main or weft thread whereof is of a size or weight greater than that of the corresponding main or weft thread or threads for the leg or instep, the said warp threads being incorporated into the fabric of the stocking under tension which in the said welt and in the said leg or instep portions, is respectively in inverse relation to the size or weight of the respective main or weft threads, thereby increasing the longitudinal expansibility of the fabric with respect to those portions of the fabric having the main or weft thread thereof of greater size or weight, such as said top welt.

12. A full-fashioned or flat-knit run-proof or strongly run-resistant stocking or blank therefor, integrally knitted in one piece from the top of the stocking through the instep and toe, and including the entire foot portion, without thread severance being compelled by the steps of stocking manufacture, said stocking or blank being composed of a main or body thread or threads knitted into all the wales from edge to edge of the fabric throughout the length thereof, and a multiplicity of warp threads in respective needle wales of the fabric, including warp threads in substantially all the needle wales of the instep of the stocking, said multiplicity of warp threads extending each in an unsevered, continuous condition lengthwise the fabric and respectively knitted in loops in successive courses in different loops of said main or body thread or threads in such courses and rendering the same runproof or strongly run-resistant, the warp threads in needle wales of the toe being all unsevered continuations of warp threads knitted into needle wales of the stocking preceding said toe.

ELLSWORTH E. CARLSON.
